Primary Examiner — Patricia A Palasik(74) *Attorney, Agent, or Firm* — William A. Bonk, III(57) **CLAIM**

The ornamental design for a security robot, as shown and described.

DESCRIPTION

FIG. 1 is a front, left side perspective view of the security robot, showing our new design;

FIG. 2 is a rear, left side perspective view of the security robot, showing our new design;

FIG. 3 is a front side elevational view thereof;

FIG. 4 is a rear side elevational view thereof;

FIG. 5 is a right side elevational view thereof;

FIG. 6 is a left side elevational view thereof;

FIG. 7 is a top plan view thereof; and,

FIG. 8 is a bottom plan view thereof.
